(57) **CLAIM**

The ornamental design for a portion of a personal grooming device, as shown and described.

DESCRIPTION

FIG. 1 is a front perspective view of a portion of a personal grooming device showing our new design;

FIG. 2 is a front view thereof;

FIG. 3 is a right side view thereof;

FIG. 4 is a top view thereof; and,

FIG. 5 is a top perspective view thereof.

The broken lines are included for the purpose of illustrating portions of the personal grooming device that form no part of the claimed design.
